VACUUM DANDRUFF HAIR BRUSH

John Raymond Smith, Box 481,
Rockingham, N.C.

Filed Nov. 24, 1958, Ser. No. 775,976
1 Claim. (Cl. 15—344)

The present invention relates to a hair brush and more particularly to a suction type hair brush for removing loose hair and dandruff during the hair brushing operation. Although the vacuum type hair brushes have previously been provided they have not been entirely satisfactory in that much of the loose hair and dandruff were not effectively collected and the structure was not easily cleaned.

An object of the present invention is to provide a vacuum type hair brush which serves to remove loose hair and dandruff during the brushing operation and which overcome some of the problems of prior art devices.

An object of the present invention is to provide a suction type hair brush which can be readily cleaned and which can be easily dis-assembled for cleaning and readily assembled for use.

A further object is to provide a filter element which can be readily removed and either thrown away or cleaned and returned to operative position.

Other and further objectives will be apparent as the description proceeds and upon reference to the accompanying drawings wherein:

FIG. 1 is a horizontal section view through the body of the assembled brush and showing the suction passageway from the bristle area to the filter and the vacuum and fan chamber from the filter and showing the motor in plan and also showing the connection of the motor to the brush head;

FIG. 2 is a section on line 2—2 of FIG. 1 showing the brush with the motor disassembled and some of the bristles omitted showing the passages for air with arrows indicating the direction of movement of the air;

FIG. 3 is an elevation of the filter element and the cooperating cap for retaining the filter in position.

Upon more detailed reference to the drawings, the hair brush comprises a brush head body 10 of suitable material with bristles 11 extending from one side thereof and around the periphery of the brush head to provide a chamber within the peripheral bristles. Such chamber within the bristles communicates by means of a suction passageway system having a plurality of small passageway portions 12 communicating from the chamber within the bristles to diagonal passageways 13 which communicate with a longitudinal passageway 14 to a transverse filter receiving bore 15. Said passageways 12, 13 and 14 provide a suction passageway system from the bristle area to the transverse substantial cylindrical bore 15. A hollow cylindrical filter element 16 provided with a conical tip 17 is received in transverse bore 15 with the tip 17 in a conical recess 18 in the end of the transverse bore 15. The filter element 16 is provided with positioning lugs 18A which cooperate with slots 19 to position the filter element in proper operative position. The filter element includes spaced perforated sections 20 with a central section 21 therebetween the central section being provided with an inlet aperture 22 which registers with a circumferential groove 23 communicating with suction passageway 14 for carrying hair and dandruff by the stream of air into the filter element 16.

The filter is held in correct position by means of a cap 24 having male threads threaded into female threads in the brush body 10.

2

The brush head is provided with a vacuum passageway 25 which is out of communication with the suction passageway and is in communication with the perforated sections 20 of the filter element. The vacuum passageway includes an internally threaded female coupling portion 26 which receives a threaded male nipple 27 on the handle which carries an electric motor 28. Motor 28 has shaft extension 29 which carries a fan 30 with a fan being of a size to be received within the vacuum passageway 25. It will be noted that the nipple 27 is hollow and is provided with outlet means 31 for the passage of filtered air from the vacuum passage 25.

It will be apparent that the parts may be readily assembled and disassembled and that the structure provides a relatively large fan receiving chamber in the female coupling member 26 whereby the structure is effective for the purpose described.

It will be noted that air passing from the suction passageway must make two substantially right angle turns which assists in the removal of the dandruff and hair from the stream of air while the small apertures 20A in the apertured sections 20 additionally assure effectively filtering the remaining dandruff and hair from the air passing therethrough.

25 What I claim is:

A hair brush comprising a brush head having bristles along the periphery thereof, said brush head being provided with a suction passageway extending from aperture means surrounded by the bristles of the brush head 30 and extending toward one end of the brush head, said brush head being provided with a transverse substantially cylindrical bore communicating with said suction passageway from the bristle area, said brush head being provided with a vacuum passageway extending from said transverse bore and separated from said suction passageway from the bristles by said transverse bore, a hollow cylindrical filter element removably mounted in said transverse bore and having a peripheral inlet opening in communication with the suction passageway from said bristles, and having small holes for filtering the loose hair and dandruff and retaining such loose hair and dandruff in the cylindrical filter element, said vacuum passageway in said brush head extending from areas surrounding the portions of the filter element provided 40 with the small apertures and terminating in a female coupling element, to provide a large fan receiving chamber, a handle for said brush, a motor in said handle and having a shaft projecting a sufficient distance to extend into the fan receiving chamber of said brush head, a fan on said shaft, said handle including a nipple portion detachably received in the female coupling portion of said brush head whereby the fan may be readily inserted into the fan receiving chamber, outlet air exhaust means disposed on the handle side of said fan, and means to positively detachably secure said nipple in said female coupling, and means to provide registration of the inlet opening to said filter element and the said suction passageway from said bristles, and removable means to close the transverse bore and retain the filter element 45 therein and to provide for removal of the filter element.
